UNITED STATES PATENT OFFICE.

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

BRAKE-BEAM GUIDE.

Application filed January 21, 1924. Serial No. 687,666.

To all whom it may concern:

Be it known that I, EDWIN G. BUSSE, a citizen of the United States, residing at Chicago, Illinois, have invented a certain new and useful Improvement in Brake-Beam Guides, of which the following is a specification, such as will enable others skilled in the art to which it appertains to make and use the same.

10 My invention is an improvement in railroad rolling stock and relates particularly to third and fourth point supports and guiding means for brake beams.

The object of my invention is to provide third and fourth point supports which guide the application of the brake shoe to the wheel as well as performing the ordinary function of acting as safety means to prevent the dropping of the brake beam assembly on the rails. Also to provide a combination third and fourth point support and guide member which will permit the reversal of the brake shoe when it becomes worn.

25 In the drawings—

Figure 1 is a side view of a preferred style of my improved brake beam supporting and guiding means.

Figure 2 is a top plan view of Figure 1.

30 Figure 3 is a view similar to Figure 1 and showing a modification.

Figure 4 is a top plan view of Figure 3.

Figure 5 is a fragmentary section similar to Figures 1 and 3 and illustrates another 35 modified construction.

The numeral 1 in the drawings is the usual spring plank. 2 is a brake beam having attached thereto the usual brake head 3 which is supported by a hanger 4. Attached to spring plank 1 by a rivet 5 is a bracket member 6 which is a strap extending from the underside of said spring plank 1 and which is bent vertically upward, then is bent backwardly in an incline to extend 40 over spring plank 1, then downwardly a short distance, then forwardly, this last bend bringing the end immediately under and in a plane parallel to the inclined portion. 7 is a slot in the bend between the two parallel portions and 8 is a second slot opposite slot 7 in the upper end of the vertically disposed portion. The function of these slots is hereinafter explained.

45 9 is a step-shaped guide member, preferably a steel strap, one end of which lies

under the brake beam and the other end being inserted through slots 7 and 8 of bracket member 6. The height of the step in member 9 is slightly greater than the height of brake beam 2 and a third strap 10 is riveted 60 to strap 9 and extends over brake beam 2 so that the inside surfaces of strap 10 and the strap 9 are parallel. A bolt 11 is passed through the side of brake beam 2 and the vertical portion of strap 9 to guide coil 65 springs 12 and 13, one of which is placed on either side of strap 9. A nut 14 on the end of bolt 11 holds spring 12 and the bolt in place.

In operation, when the brakes are applied, the guide member 9 slides forwardly through slots 7 and 8 until the difference in the arc of movement of brake beam 2 which pivots from the brake hanger support (not shown) causes the guide to become wedged between 70 the parallel guiding portions of bracket strap 6. If the necessary movement is not yet completed, the brake beam may slide forwardly relative to strap 10 and the forward portion of strap 9, thereby compressing 75 spring 13. The forward movement of the brake beam relative to the guide member is limited by the spring 13 and bolt 11 and by the clearance between the brake beam and the guide members. These parts would 80 eventually wedge due to the twisting of the brake beam. When the brakes are released the parts resume their normal positions, the springs 12 and 13 recentering brake beam 2 in relation to straps 9 and 10 and the backward movement of the assembly unwedging 85 strap 9 in the bracket 6. At all times the assembly prevents any marked upward or downward movement of the brake beam. With this type of guide and the flexibility 90 of movement which it permits, it is wholly practical to reverse a brake shoe in case one side is unduly worn.

In Figure 3 a modification is shown in which a steel strap 15 is bent vertically upwardly 100 from under spring plank 1 and then back over the spring plank slightly inclined to the horizontal. A slot 16 is cut just below the upper bend. A steel strap 17 is the guide member in this form and is passed through slot 16. It extends outwardly from slot 16 and is then curved back under itself, then downwardly, then forwardly, to enclose 105 brake beam 2, and a pair of coil springs 18 and 19 which are mounted one above the 110

other between the back of brake beam 2 and the forward side of the vertically disposed portion of strap 17. Bolts 20 and 21 are passed through brake beam 2 and strap 17 to 5 guide springs 20 and 21 and hold them in place. Nuts 22 and 23 lock bolts 20 and 21 in place.

The operation of this form is very similar to the other, the principal difference being 10 that a practically unlimited upward twist or movement of the brake head is permitted since there is only a single guiding surface in the bracket 15. A downward twist or movement is limited the same as in the preferred form and restoration of the position 15 of the parts being similarly effected.

In Figure 5 the bracket 24 and guide 25 extend downwardly from the spring plank and beam, respectively, but the relative position of the parts and their functions are practically the same. In this construction the lower face of the spring plank serves 20 as one of the guiding surfaces for the beam member 25. Where other truck equipment 25 or other reasons prevent the preferred mounting of the bracket and guide, this arrangement may be substituted.

In each of these forms there is present a 30 bracket member, a guide member slidably therein, and a yielding mounting of the beam on the guide member. The bolt and nut provide means for adjusting the resistance of the springs. While I prefer to make the bracket and guide rigid elements, it is 35 obvious that they could be made of spring material to increase the flexibility of the devices.

Other modifications of my invention may 40 be made without departing from the scope thereof as expressed in the appended claims.

I claim:

1. In a car truck, a fixed member, a brake beam, a guide element yieldingly connected to said beam, and a sliding connection between said guide element and said fixed member.

2. In combination, a spring plank, a brake beam, a guide element yieldingly secured to said beam and extending over said spring plank, and a sliding connection between said element and said brake beam.

3. In combination, a spring plank, a brake beam, a guide element yieldingly secured to said beam extending over said spring plank, and means mounted on said spring plank for directing sliding movement of said element over the plank.

4. In a car truck, a brake beam, a guide element yieldingly attached thereto, and a fixed truck member slidably mounting said element.

5. In combination, a spring plank, an up- 65 standing bracket thereon having a leg above said plank inclined to the horizontal, a brake beam, a brake beam guide having a leg sub-

stantially parallel to and movable longitudinally in relation to the said bracket and leg, and a yielding connection between said guide and said beam.

6. In combination, a spring plank, an up- 70 standing bracket thereon having a leg above said plank inclined to the horizontal, a brake beam, a brake beam guide having a leg sub- 75 stantially parallel to and movable longitudinally in relation to the said bracket and leg, and a limited spring connection between said guide and said beam which maintains the normal relative positions of the parts.

7. A brake beam guide and support comprising a fixed truck member having a 80 bracket attached thereto, a brake beam, a guiding and supporting member slidably connected to said bracket, and a limited sliding connection between said brake beam and said guiding and supporting member.

8. A brake beam guide and support comprising a fixed truck member having a 85 bracket attached thereto, a brake beam, a guiding and supporting member slidably connected to said bracket and having limited 90 movement relative to said beam.

9. In a car truck, a fixed member having spaced parts, a guide slidably mounted between said spaced parts, a brake beam, and a sliding connection between said beam and said guide.

10. In a car truck, a fixed member having spaced parts, a guide slidably mounted between said spaced parts, a brake beam, and a limited sliding connection between said beam and said guide.

11. In a car truck, a spring plank, an up- 100 wardly disposed bracket mounted thereon having a portion inclined back over said plank, a slot in said bracket, a guide member slidably mounted in said slot and held against downward movement by said inclined portion, a brake beam, and a spring connection between said guide and said beam which resists relative displacement of the 110 parts.

12. In a car truck, a fixed member, a guide member slidably connected thereto, a brake beam, positioning springs connecting said beam and said guide member to maintain the proper relationship of the parts.

13. In a car truck, a fixed member, a brake beam, a guide element slidably connected to said fixed member, and means on said element for positioning its relation to said beam.

14. In a car truck, a spring plank having mounted thereon an upright bracket, a portion of which is inclined back over said plank, then spaced from and bent under and parallel to the inclined portion, oppositely disposed slots in said bracket at each end of said parallel portions, a guide member slidably mounted in said slots and held against unusual upward or downward move- 130

ment by said parallel portions, a brake beam, and a spring connection of limited movement between said guide member and said beam.

5 15. In a car truck, a fixed member, a brake beam, a brake beam guide and support having a yielding connection with said brake beam and a connection with said fixed member.

16. In a car truck, a fixed member, a 10
brake beam, a brake beam guide and sup-
port having a sliding connection with said
brake beam and a connection with said fixed
member.

In testimony whereof I hereunto affix my 15
signature this 17th day of January, 1924.

EDWIN G. BUSSE.
